TUFTING BUTTON

Wilfred B. Mathewson, Quincy, Mass., assignor
to United Mattress Machinery Company,
Quincy, Mass., a Corporation of Maine

Application February 7, 1933. Serial No. 655,588

4 Claims. (Cl. 24—90)

This invention relates to tufting buttons such as are used in tufting mattresses, upholstery and the like and one of the objects is to provide a tufting button which is constructed so that it can be easily applied and fastened to a loop of tufting tape or tufting cord which has been previously inserted in a mattress or other piece of upholstery.

Another object of the invention is to provide a novel tufting button constructed as above described which will not chafe or wear the tufting cord or tufting tape.

Other objects of the invention are to improve tufting buttons in various ways which will be more fully hereinafter set forth.

The tufting button herein shown is also constructed so that it can be applied and fastened to the loop of tufting cord by means of the button-fastening device illustrated in my co-pending application Serial No. 653,277, filed January 24, 1933.

One form of the tufting button is shown in the accompanying drawing wherein:

Fig. 1 is a back side view of the tufting button embodying my invention showing it before it is applied to the tufting cord or tufting tape;

Fig. 2 is a section on the line 2—2, Fig. 1;

Fig. 3 is a section similar to Fig. 2 but showing the tongue in its closed position, that is, the position it assumes after the tufting button has been fastened to the tufting cord or tufting tape;

Fig. 4 is a sectional view showing a tufting button embodying my invention fastened to the loop of tufting tape, the section through the button being taken on the line 4—4, Fig. 3;

Fig. 5 is an under side view of the button showing said button attached to the tufting tape;

Fig. 6 is a section on the line 6—6, Fig. 5.

The tufting button herein shown is indicated generally at 1. It is formed with a front or face member 2 and a rear or back member 3, these two members being formed of sheet material and being united at their peripheral portions as shown at 4, this being a common way of making a tufting button.

In my invention the back portion 3 of the tufting button has struck up therefrom a tongue 5 and when the button is first made and before it is applied to the thread loop said tongue 5 extends at an angle to the back face 3 for the greater portion of its length as shown in Fig. 2 and the front edge portion 6 of the tongue is bent at an angle to the body thereof and into a position which is substantially parallel to the back portion 3 of the button. The portion of the tongue which has the angular relation to the back 3 constitutes

the cord-engaging portion thereof and the front edge portion 6 which extends substantially parallel to the back 3 constitutes an end portion. The end portion 6 is of a smaller dimension in the direction of the length of the tongue than the 60 cord-engaging portion.

The edges 8 of the tongue are deformed by being bent outwardly as shown at 7, such outwardly-bent portions preferably having a concavo-convex shape in the direction of the length 65 of the button. This produces a concave depression in each side edge 8 of the button, each depression extending from the root or base of the tongue to a point 9 where the bent lip 6 meets the body of the tongue. The depressions are 70 deepest at the central portion thereof and have a progressively decreasing depth from the center portion toward the base of the tongue and the point 9.

The side edge portions 10 of the opening in 75 the back 3 of the button from which the tongue 5 is struck are also deformed by being bent inwardly thereby to form depressions 11. The depressions 11 are also concave in the direction of the length of the side edge of the slit and 80 are, therefore, deepest at their center portion and they extend from the base of the tongue to a point 12. Said depressions 11 are deepest at their central portion and have a progressively decreasing depth from the central portion to the 85 base of the tongue in one direction and to the point 12 in the other direction.

In using the button having the above construction loops 13 of tufting tape or tufting cord are inserted through the mattress, a portion of which is indicated at 14 in Fig. 4, a portion 15 of each loop being exposed on the outside of the ticking 16 of the mattress.

When the button is applied to the loop it has the shape shown in Figs. 1 and 2, that is, the 95 tongue 5 is projecting from the back of the button thereby to form a throat 17 between the back of the button and the tongue 5.

In applying the button to the loop the projecting tongue 5 is forced underneath the portion 15 of the loop until the loop enters the depressions 7 formed in the sides of the tongue. At this time the loop embraces the tongue and passes through the depressions 7. The tongue is then closed up or bent from its open position shown in Fig. 2 to its closed position shown in Fig. 3. In its closed position the body portion of the tongue will assume a position substantially in the plane of the back 3 of the button 100 as shown in Fig. 3 and the lip 6 at the end of 105 110

- the tongue will be forced through the opening 18 in the back of the button and will project inside of the button slightly. When the tongue is thus closed up the edges of the tongue at 5 the point 9 where the depressions 7 terminate are in engagement with the side walls of the opening 18 in the back 3 of the button at substantially the points 12 just in front of the depressions 11. When the tongue is thus closed 10 the depressions 11 in the back of the button are opposed to the depressions 7 in the tongue and each pair of opposed depressions forms an eye or opening 19 through which the loop of tufting cord or tufting tape passes as best seen in 15 Figs. 4 and 5. These eyes or openings 19 are closed eyes by reason of the fact that the side edges of the tongue at the points 9 have engagement with the side edges of the opening 18 at the points 12.
- 20 The shape of the depressions 7 is such as to provide the tongue when closed with a rounded cord-receiving seat as shown in Fig. 4 thereby eliminating any chafing of the cord or tape due to passing over sharp corners.
- 25 The deformation of the back 3 of the button to form the depressions 11 carries the edges of the opening 18 inwardly beyond the cord or tape so that the side edges of the opening 18 cannot chafe or injure the cord or tape.
- 30 Hence when the button is applied to the loop of tufting cord or tufting tape it is firmly locked to the loop and in such a way that the cord or loop will not be injured by chafing against sharp corners.
- 35 The button herein shown is well adapted to be fastened to the loop by the button-fastening device shown in my above-mentioned co-pending application Serial No. 653,277. The device of this application is provided with means for holding a button and inserting it in position with the open tongue underneath the loop of tufting cord and then closing the tongue to lock the button to said loop.
- 40 When the tongue is closed thereby to lock or fasten the button to the loop of tufting cord or tufting tape the lip 6 is carried through the opening 18 so that it projects inwardly from the back of the button as shown in Figs. 3 and 6.
- 45 An advantage of this construction is that even though in the operation of closing the tongue said tongue should not be forced clear into the plane of the back 3 yet the edge of the tongue will still be carried through the opening 18 so that the button will have no projecting edge on its back face except the rounded edges formed by the depressions 7.

I claim:

1. A tufting button having struck up from the back thereof a tongue which extends outwardly at an angle to the back of the button and the front edge of which is bent to form a lip extending substantially parallel to said back, the side edges of the tongue being bent outwardly and the side edges of the opening from which the tongue is struck being bent inwardly, said tongue being bendable into closed position in substantially the plane of the back of the button and the bent side edges of the tongue and said opening forming closed cord-receiving eyes. 80

2. A tufting button having struck up from the back thereof a tongue presenting a cord-engaging portion and an end portion, said cord-engaging portion occupying the plane of the back of the button and said end portion being bent inwardly from the cord-engaging portion toward the inside of the button when said tongue is in closed position, the side edges of the tongue between said end portion and the root of the tongue being bent outwardly beyond the plane of the back. 90

3. A tufting button having struck up from the back thereof a tongue presenting a cord-engaging portion and an end portion, said cord-engaging portion occupying the plane of the back of the button and said end portion being bent inwardly from the cord-engaging portion toward the inside of the button when said tongue is in closed position, the side edges of the tongue between said end portion and the root of the tongue being bent outwardly beyond the plane of the back and the side edges of the opening from which the tongue is struck being bent inwardly, whereby two closed cord-receiving eyes are formed through which the loop of tufting cord passes. 105

4. A tufting button having struck up from the back thereof a tongue presenting a cord-engaging portion and an end portion, said cord-engaging portion being substantially straight in the direction of the length of the tongue and extending outwardly from the back of the button at a wide angle thereto, and the end portion having considerably less dimension in the direction of the length of the tongue than said cord-engaging portion and extending substantially parallel to said back, said tongue being adapted to be bent inwardly into a position with the cord-engaging portion occupying the plane of the back of the button and the end portion located within the button. 115
